GARMENT

Henry H. Bruderlin, Venice, Calif.

Application September 23, 1947, Serial No. 775,704

6 Claims. (CL 2-42)

1

This invention relates to brassières and is directed more particularly to brassières of the so-called "strapless" type which are supported on the body of the wearer without the assistance of the usual straps passing over the shoulders and attached to front and rear portions of the garment. The present invention constitutes an improvement over the brassière disclosed in my co-pending application, Serial No. 713,546, filed December 2, 1946.

There are several varieties of "strapless" brassières already known but none of them has been found to be entirely satisfactory. The simplest type is little more than a conventional brassière with the shoulder straps removed and is held in place by high circumferential tension. The disadvantage of this type is obvious when it is considered that the body circumference expands and contracts two inches or more in normal breathing. If the garment is tight enough with the breath exhaled it will be too tight with the breath inhaled, and therefore it restricts normal breathing. On the other hand, if the tension is reduced sufficiently to allow normal breathing with comfort, it will be too loose to stay in place with the breath exhaled. Efforts have been made to overcome this difficulty by the use of elastic material at some point in the periphery but elastic material in tension cannot accommodate this much change in dimension without excessive tension which causes discomfort.

In order to insure that this type of brassière does not slip downward, it is necessary to provide tie material at the front center of the garment at a level near the top of the cups. Consequently this type is not suitable for use with dresses having deep necklines since the tie member would be visible.

Another type makes use of substantially the same basic member described above but includes wire stays of various kinds adapted to stiffen or support local areas of the brassière. While this type is generally more satisfactory, it is not a complete solution to the problem because it is likewise maintained in position only by circumferential tension in the fabric which results in the disadvantages mentioned above.

Another drawback of all types of strapless brassières known up to this time is that they require a band across the back, usually including a detachable fastener in the center of the back. In addition to the inconvenience of such an arrangement, the back strap, in the case of a bathing suit brassière, precludes the possibility of building up an even coat of tan across the back.

2

Consequently, a woman who wears a bathing suit provided with such a brassière is unable to wear a backless evening gown because of the unsightly mark produced.

The invention described in my co-pending application overcomes all of the difficulties presented by previous types of brassières and also possesses various additional advantages as outlined in said application. The present invention provides a more simplified construction possessing practically all of the advantages of my previous invention and incorporates several improvements thereover.

As in the previous case, the brassière of this invention incorporates a completely self supporting frame and does not rely for any of its support on the fabric of the brassière proper which is therefore free to perform the sole function of supporting the breasts. It also eliminates the necessity for a back strap together with its fastening member.

The present invention contemplates a unitary frame structure formed of one or more lengths of slender, elongate, resilient material. It may be made of wire or of a plastic material such as "Lucite," which has considerable elasticity, the presently preferred material being stainless, rust resisting spring wire having a diameter of about three thirty-seconds of an inch or slightly less. The frame is of generally C-shape in horizontal projection to conform to and resiliently grip the body of the wearer and defines in general a figure 8 in vertical projection, providing two loops serving as breast receiving openings. The frame is covered with a brassière body of fabric or other suitable material substantially of conventional form provided with a pocket member to receive the frame. Expansion of the chest resulting from normal breathing is accommodated by yielding of the spring material in bending with very little change in the light, resilient pressure of the frame on the body.

The wire elements making up the frame cross each other at the plane of symmetry and are free to move with respect to each other. The frame in my co-pending application includes an element at the lower edge extending entirely across the central portion. When it is incorporated in a garment such as a one-piece bathing suit, this element tends to form an unsightly projection. However, in the present invention, the lower frame elements rise as they approach the center line, following the form of the body more closely, and thus eliminate the projection mentioned above.

The fact that the frame has a minimum vertical projection at the plane of symmetry plus the torsional resilience of the frame material results in a structure which will flex readily to follow any irregular movements of the body. Means are provided, in a modified form of the invention, to adjust the relation of the elements for the purpose of varying the vertical extent of the frame to provide a different outline.

While the invention is illustrated as being applied to a garment commonly known as a brassière, it will be apparent that the frame member may be attached directly to any type of garment, such as a one-piece bathing suit, a slip, a formal gown or the like.

Other features and advantages will become apparent as the description proceeds.

While the invention may take numerous forms, those which are presently preferred are illustrated in the accompanying drawing in which.

Figure 1 is a three-quarter rear view in perspective of one form of the brassière frame of this invention with the cover removed;

Figure 2 is a rear elevational view of said frame with the cover in place, but with a portion thereof broken away;

Figure 3 is a top plan view of the frame;

Figure 4 is a side elevational view of the frame; and

Figure 5 is a rear elevational view of a modified form of the frame incorporating shape adjusting means.

Referring first to Figure 1, the basic frame, generally indicated by reference character 10, is made up of two elements 12 and 14 of slender, elongate, resilient material, such as spring wire. These elements are symmetrical with respect to each other and are provided with three-dimensional curves. Thus, element 12 has a left hand portion 16 provided with an upwardly convex arch and having a reverse curve in planform, and a right hand portion 18 lying generally in a horizontal plane and having a reverse curve in planform.

Right and left hand portions 20 and 22 of element 14 are complementary to portions 16 and 18, and the elements are joined at their ends 24 and 26, as by welding in the case of wire or cementing in the case of plastic. Any other desired method of connection may be used, and the entire frame may be made from a single length of material having a single connection at any desired point. It is to be understood that the term "element" as used in the subjoined claims is intended to define not a separate piece of material joined to other pieces of material but rather such part of any entire frame as is indicated by the terms of the particular claim.

It will be seen from Figures 2 and 3 that elements 12 and 14 cross over each other substantially at the plane of symmetry of the frame and that together they form in general a figure 8 in vertical projection and a C-shape in horizontal projection, with the arched portion of one element lying generally above the horizontal portion of the other element, thus defining a breast receiving opening at each side of the plane of symmetry. The C-shape of the entire frame, as seen in Figure 3, conforms to the body of the wearer and, because of the nature of the material, resiliently but firmly grips the body. Expansion of the chest increases the radial dimensions and causes corresponding expansion of the frame. This is taken care of by outward bending along the entire length of the frame and, since the bending at any

one point is very slight, the increase in radial pressure is negligible. This feature makes one frame adaptable to a relatively large range of chest sizes.

The elements of the frame are free to move with respect to each other where they cross in order to permit the frame to follow every movement of the wearer. They separate only slightly even with extreme movements but, if desired, a loop or link 28 may be provided as indicated in Figure 1 to loosely encircle both elements and limit the extent of such separation.

The brassière is completed by the provision of a cover member mounted on the frame in a novel manner. A first piece of material 30 of the type conventionally used in brassières is provided with an outline corresponding to that of the frame but slightly larger. The usual cup portions 32 and 34 are formed therein as indicated in Figure 2. A second piece of material 36 of the same conformation is attached to the first piece along a line corresponding with the outline of the frame to form a pocket completely enclosing the frame and having a relatively narrow center portion, as at 38, with a wider portion to each side thereof.

At one free end of the cover the material of member 30 terminates slightly short of the extreme end, as at 40 and a small flap member 42 is provided to complete the covering. This flap member slightly overlaps edge 40, terminating at 44 to provide an entrance to the pocket. The other free end of the cover may be completely closed or it may be formed in the same manner as the first free end. To insert the frame in the cover, it is progressively collapsed and inserted thru the opening formed by parts 40, 42, 44. After it has been inserted, it expands to completely fill out the pocket and the brassière is ready for use, with flap 42 covering the last entering portion of the frame.

Tabs 46 and 48 are provided on the cover member in case it is desired to attach shoulder straps for added uplift, and tabs 50 are provided for the attachment of back tie members which may be furnished on swimming suit brassières. These tie members may be tucked under the ends of the brassière cover when not needed.

When the invention is applied to any more extensive garment a piece of material such as 30 or 36 is attached, as by sewing, to the main garment in the appropriate location to form a pocket therewith for the reception of the frame in the manner above described. Instead of using a pocket, the frame may be sewed directly in position in the garment if desired.

Means are provided in the modification illustrated in Figure 5 for altering the shape of the frame. Elements 52 and 54 are each provided with two detents 56 and 58 in the form of short reverse bends. Upper and lower loops or links 60 and 62 loosely encircle the two elements. When these loops lie together at the point of crossing, the frame has the shape of Figures 1 to 4. However, when the loops are moved to the position shown in Figure 5 they draw the adjacent portions of elements 52 and 54 together into a more nearly vertical position and the frame consequently becomes higher and narrower. Similarly, rearrangement of the loops and detents may provide for making the frame flatter and wider than normal.

It will be seen that the novel type of brassière herein disclosed is suitable for all types of wearing apparel and provides maximum comfort and convenience while eliminating the discomforts

75 and disadvantages of previously known types.

While several preferred forms of the invention have been illustrated and described hereinabove, it will be apparent that various changes and modifications may be made without departing from the invention, and it is intended that all such changes and modifications shall be embraced within the scope of the following claims.

I claim:

1. A frame for a garment comprising: a structure of filamentary resilient material; the elements of said structure defining a closed loop at each side of the plane of symmetry to serve as a breast receiving opening; the free ends of said loops being curved out of the general vertical plane of the medial portion, but lying substantially in the horizontal plane of the lower edge of said frame, to define therewith a generally C-shape to conform to and grip the body of the wearer; and the adjacent portions of said loops being so connected to each other as to be capable of substantial resistance to bending.

2. A frame for a garment comprising: a slender elongate element of resilient material defining an open framework in the general form of a figure 8; one loop of the figure being located at each side of the plane of symmetry of the frame; each loop expanding rapidly adjacent the plane of symmetry and converging gradually to a relatively small arcuate free end; said element crossing over itself loosely at the juncture of the loops at the plane of symmetry; said framework being curved generally in a C-shape to conform to and resiliently grip the body of the wearer.

3. A frame for a garment comprising: a unitary structure of filamentary resilient material generally defining a C-shape in horizontal projection and a figure 8 in vertical projection; the elements of said structure crossing each other substantially at the plane of symmetry and being free to move with respect to each other; a detent formed on each element closely above and below the point of intersection; and tie means engaging the detents to alter the shape of the frame.

4. A woman's garment comprising: a unitary frame structure of filamentary resilient material generally defining a C-shape in horizontal projection and a figure 8 in vertical projection; the elements of said structure crossing each other substantially at the plane of symmetry and being free to move with respect to each other; and a garment member having breast supporting portions and provided with a single pocket member having substantially the same form as the outline of said frame structure and having a relatively small opening at one end; said frame struc-

ture by virtue of its resiliency being adapted to be temporarily deformed to insert it in said pocket member.

5. A frame for a garment comprising: a co-extensive pair of elements of filamentary resilient material, each of said elements extending unbrokenly from end to end of said frame across the plane of symmetry thereof and the ends of said elements being joined to each other at said frame ends; said elements being arranged to cross each other in the general form of an X at the plane of symmetry of said frame to form a generally vertical frontal plane; the upper portion of each element in said frontal plane defining an upwardly convex arch; the lower portion of each element in said frontal plane being substantially horizontal and lying substantially directly below the arched portion of the other element to define therewith a breast receiving opening; both ends of each element being curved rearwardly out of said frontal plane to extend around and resiliently grip the body of the wearer.

6. A frame for a garment comprising: a plurality of slender elongate elements of resilient material fixedly joined to each other to define a unitary open framework in the general form of a figure 8; one loop of the figure being located at each side of the plane of symmetry of the frame; each loop expanding rapidly adjacent the plane of symmetry and converging gradually to a relatively small free end; said elements crossing over each other loosely at the juncture of the loops at the plane of symmetry; said framework being curved generally in a C-shape to conform to and resiliently grip the body of the wearer.
